LAMP CHANGER

Leslie C. Hays, Healdsburg, Calif.

Application December 16, 1944; Serial No. 568,465

9 Claims.

(Cl. 294—20)

This invention relates to, and it is an object to provide, a novel electric globe or lamp changing device of the pole type used to change lamps which are disposed at elevated but exposed points, such as depending street lamps.

Another object of the present invention is to provide a pole type lamp changer which includes a unique lamp engaging clamp assembly operative to effectively frictionally engage and rotate a lamp for the purpose of placement or removal thereof from an elevated socket.

A further object of this invention is to provide a lamp changer, as in the preceding paragraph, in which the clamp assembly includes a lamp engaging head disposed beyond the upper end of the pole and mounted for movement axially of the latter, opposed clamps arranged to frictionally engage the lamp on opposite sides of and beyond said head, and operating connections between said head and clamps arranged to cause inward movement of the clamps into clamping contact with opposite sides of the lamp upon engagement of the lamp at its outer end with the head and movement of the latter by said lamp toward the upper end of the pole, whereby upward pushing on the pole forcefully and frictionally clamps the lamp so that considerable turning force may then be applied thereto by said pole.

A further object of the invention is to produce a simple and inexpensive device, and yet one which will be exceedingly effective for the purpose for which it is designed.

These objects are accomplished by means of such structure and relative arrangement of parts as will fully appear by a perusal of the following specification and claims.

In the drawing similar characters of reference indicate corresponding parts in the several views;

Figure 1 is a vertical, side elevation of the lamp changer.

Figure 2 is a vertical sectional elevation on line 2—2 of Fig. 1.

Figure 3 is an enlarged, vertical side elevation of the lamp clamping assembly as in use.

Figure 4 is a top plan view of said assembly.

Referring now more particularly to the characters of reference on the drawing, the improved lamp changer comprises an elongated pole 1 connected at its upper end in axial alignment with a relatively short tubular neck 2 by means of a close coupled, heavy-duty helical spring 3.

The tubular neck 2 is formed, intermediate its ends, with opposed longitudinal slots 4, and a cylindrical slide block 5 is slidably disposed in

neck 2 with a relatively close running fit. Headed screws 6 and 7 extend through corresponding slots 4 and are threaded into the slide block 5, washers 8 surrounding the screws 6 and 7 under the heads thereof and riding against the outside of the tubular neck 2 along the corresponding slots 4. The screw 7 is of somewhat greater length than the screw 6, and is surrounded between its head and the corresponding washer 8 by a compression spring 9 which serves to frictionally maintain the slide block 5 in any position of adjustment in the tubular neck 2.

At its upper end the tubular neck 2 is formed with an enlarged annular cap plate 10 of a diameter greater than said neck, whereby the plate has a considerable overhang beyond the neck.

A plunger stem 11 is disposed within the tubular neck 2 centrally thereof and projects adjacent its upper end and in guided relation through a center opening 12 in the cap plate 10. At its upper end and beyond said cap plate the stem 11 is fitted with an annular head 13 which is concave on top; said head being of substantially lesser diameter than the cap plate 10.

The lower end portion of the plunger stem 11 projects through an axial bore 14 in the slide block 5; said block being normally but adjustably secured to the stem 11 by engagement of the screws 6 and 7 therewith.

Above the head 13 the device includes a pair of inwardly and slightly downwardly facing arcuate jaws 15 having a friction lining or facing 16 on adjacent faces thereof, which lining may be a rubber or cork pad for frictionally gripping the lamp to be changed.

A pair of spring wire fingers 17 are fixed to each jaw 15 at the back thereof and thence depend in side by side, relatively loose-play relation through corresponding openings 18 in the enlarged cap plate 10 laterally out from opposite sides of the tubular neck 2. After passing through the openings 18 the spring wire fingers depend some distance therebelow to adjacent the slide block 5.

Corresponding ones of the pairs of fingers 17 converge relative to each other on opposite sides of the tubular neck 2 and intersect, as at 19, between the slide block 5 and cap plate 10. Below said point of intersection, the intersecting wires diverge and at their lower ends are formed with inturned portions 20 which are fixed to the washers 8.

In operation of the above described lamp changer, and when it is desired to remove a lamp from an elevated socket, the slide block 5 is man-

ually advanced in the tubular neck 2, which causes the angle of convergence of the intersecting ones of the fingers 17 to be increased below the cap plate 10, which in turn causes the jaws 15 to be moved apart correspondingly; the cap plate 10 about the openings 18 forming a fulcrum for said fingers. At the same time the head 13 is advanced upwardly relative to said cap plate 10. The operator then raises the device and engages the head 13 against the outer end of the lamp 21, and continues to push upwardly on the pole 1. This results in a relative downward movement of the plunger stem 11 and slide block 5, which in turn draws the spring fingers 17 downwardly through the cap plate 10. With such downward movement of the spring fingers, with consequent decrease in the angle of convergence below said plate, the jaws 15 swing inwardly and engage opposite sides of the lamp 21 with a relatively tight grip.

The operator, while maintaining an upward force on pole 1, rotates the same, which unscrews the lamp 21 from its socket and permits it to be lowered to floor or ground level for access.

To place a new lamp in an elevated socket, from which a burned-out lamp has been removed, the above described operation is merely reversed.

In order to permit the jaws 15 to engage with a lamp which may project laterally rather than depending, a pull-cord 22 is attached to a ring 23 which turnably extends about the cap plate 10. To engage a laterally projecting lamp the operator pulls down on the cord 22, which causes the helical spring 3 to bend, whereupon the jaws 15 may be engaged with the lamp.

In order to adjust the clamping assembly for different sized lamps, or to increase or decrease the jaw tension on a lamp of given size, the relative position of head 13 to the jaws 15 axially of the device is varied by loosening the screws 6 and 7 and adjusting the slide block 5 on stem 11. It will thus be seen that an adjusted throw of the jaws 15 may be obtained for any given axial movement of the head 13 toward the cap plate 10.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent is desired:

1. A lamp changer comprising a pole, a pair of opposed lamp engaging jaws disposed beyond the upper end of the pole, means mounting the jaws in connection with the pole for relative approaching or separating movement, a lamp engaging element disposed beyond the upper end of the pole, means mounting said element in connection with the pole for relative axial movement, and means operative upon such movement of said element toward the pole to cause approaching movement of the jaws.

2. A lamp changer as in claim 1 in which said element is disposed substantially centrally between but below said jaws.

3. A lamp changer comprising a pole, a pair of lamp engaging jaws disposed beyond the upper end of the pole, opposed spring fingers support-

ing the jaws from the pole, a plunger mounted on the pole and projecting beyond its upper end between said opposed fingers, a lamp engaging element on the upper end of the plunger, and means arranged to cause the opposed fingers to swing the jaws toward each other upon downward movement of said plunger.

4. A lamp changer comprising a pole, a pair of lamp engaging jaws disposed beyond the upper end of the pole, opposed spring fingers supporting the jaws from the pole, a plunger mounted on the pole and projecting beyond its upper end between said opposed fingers, a lamp engaging element on the upper end of the plunger, said opposed fingers being arranged into connection and movable with the plunger, and means cooperating with the fingers intermediate the ends thereof to cause the upper jaw supporting ends of said fingers to approach or separate relative to each other upon downward or upward movement, respectively, of the plunger relative to the pole.

5. A lamp changer comprising a pole, a pair of lamp engaging jaws disposed beyond the upper end of the pole, opposed spring fingers supporting the jaws from the pole, a plunger mounted on the pole and projecting beyond its upper end between said opposed fingers, a lamp engaging element on the upper end of the plunger, said opposed fingers being arranged into connection and movable with the plunger, and means cooperating with the fingers intermediate the ends thereof to cause the upper jaw supporting ends of said fingers to approach or separate relative to each other upon downward or upward movement, respectively, of the plunger relative to the pole; said means comprising a member on the pole adjacent its upper end having spaced openings through which the opposed fingers extend intermediate their ends in loose play relation, said fingers converging below said member whereby upon up or down relative movement of the plunger to cause separating or approaching movement, respectively, of said fingers above the member.

6. A lamp changer comprising a pole, a pair of lamp engaging jaws disposed beyond the upper end of the pole, opposed spring fingers connected to the jaws and depending alongside the upper portion of the pole, a slide block mounted in connection with said portion of the pole, the fingers being connected at their lower ends to said block, a member on the pole above the slide block having spaced holes through which said fingers project in loose play relation, said fingers converging directly below said member, a plunger mounted in connection with said upper portion of the pole and projecting therebeyond, and a lamp engaging head on the outer end of the plunger between but below the jaws, the inner end portion of the plunger being connected to the slide.

7. A lamp changer as in claim 6 in which the plunger is axially adjustably connected to the slide.

8. A lamp changer comprising a pole having a tubular upper end portion, a slide block in said upper end portion, a stem secured to the slide block and projecting upwardly to a termination out of and above said end portion, a lamp engaging head on the upper end of said stem, a pair of opposed lamp engaging jaws disposed above said head, opposed spring fingers depending from the jaws along opposite sides of said upper end portion of the post, said upper end

portion having longitudinal slots in said opposite sides, means connecting the lower ends of the spring fingers to the slide block through said slots, and a member on the post at its upper end having spaced openings corresponding to and through which the fingers extend in loose play relation, said fingers converging directly below said member.

9. A lamp changer as in claim 8 in which said member comprises an enlarged annular cap plate on the upper end of the post, a turnable ring on said cap plate, and a pull cord depending from the ring; the pole including a resilient portion therein adjacent its upper end but below said tubular upper end portion.
